UNITED STATES PATENT OFFICE.

WOLFGANG E. SCHWARZMANN AND FREDERICK DRAKE NORMAN, OF SPRINGFIELD, MASSACHUSETTS, ASSIGNEES, BY MESNE ASSIGNMENTS, TO AMERICAN BOSCH MAGNETO CORPORATION, OF NEW YORK, N. Y., A CORPORATION OF NEW YORK.

SHAFT-COUPING.

1,338,751.

Specification of Letters Patent.

Patented May 4, 1920.

Application filed January 2, 1918. Serial No. 210,064.

To all whom it may concern:

Be it known that we, WOLFGANG E. SCHWARZMANN, a citizen of the United States, and FREDERICK D. NORMAN, a subject of the King of Great Britain, residing at Long Meadow, Springfield, Hampden county, State of Massachusetts, have invented certain new and useful Improvements in Shaft-Couplings; and we do hereby declare the following to be a full, clear, and exact description of the invention, such as will enable others skilled in the art to which it appertains to make and use the same.

The present invention relates to shaft couplings having coaxial driving and driven members which may be engaged with each other and disengaged from each other without axial movement of either member on its shaft, and it relates more specifically to a coupling of that kind particularly adapted for association with an impulse starting mechanism intended to be disconnected from the driving unit to restress the impelling spring, and to be reconnected thereto for repeating the impelling movement of the driven unit, while maintaining the driving unit in fixed angular position.

As disclosed in the application of M. Tost filed concurrently herewith, an internal combustion engine may drive the magneto associated with it for ignition purposes through impulse starting mechanism to give impelling movements to the magneto for firing the cylinder of the engine while the engine is rotating slowly in starting, or is at rest; and a releasable coupling may be connected between the engine and the impulse starting mechanism to permit the returning of the magneto to its angular position for maximum generation during the subsequent impelling movement, and also to permit the restressing of the spring while the engine is maintained in its firing position, for repeated generation of an ignition spark in case the previous spark failed to start the engine into operation under its own power.

Our invention comprehends a coupling useful for this specific organization, and also useful in shaft driving mechanism in general, wherein it is desirable at times to release the coupling members for any pur-

pose whatsoever. One of the coupling members carries a connecting device movable from a disengaged position permitting relative angular displacement of the coupling members to an engaged position with the other member so as to then hold the two members in substantially fixed angular position.

In the preferred embodiment of the coupling hereinafter described, one member thereof carries a diametrical arm, whereas the other member carries two diametrically disposed pivoted latches adapted to swing from disengaged positions to positions embracing the outer ends of the arm. A flat spring tends to hold the pivoted latches in either the disengaged or the engaged position, and prevents the latches from being thrown out from engaged position by centrifugal force acting on them during the normal operation of the magneto. Also, the diametrical arm comprises a magazine of flat springs permitting a small degree of disalignment of the shafts on which the coupling members are mounted, and also permitting easier engagement and disengagement of the latches when the shafts are disaligned.

In the case of the engine organization hereinbefore referred to, the magneto once set relatively to the engine, should not be recoupled 180° from that setting, because the predetermined order of firing the cylinders would be changed. Thus, when the coupling members are released to restress the impelling spring, they should be restored to their predetermined relation. It sometimes happens, however, that upon restressing the impelling spring, the coupling member being turned is inadvertently released before it is reconnected to the other coupling member. The magneto is then impelled freely and might be recoupled to the engine in an altered relation. In order to eliminate this contingency we provide means limiting the relative angular displacement of the coupling members when they are disengaged from each other.

In the preferred embodiment hereinafter described, the limiting means is constituted by one or more abutments carried by the latches and co-acting with the diametrical

arm to prevent angular displacement of the coupling members in one direction, and to permit a limited amount of angular displacement in the other direction.

5 In view of the fact that it is sometimes desirable to provide for a rotation of the magneto or other driven device in clockwise direction, and sometimes in anti-clockwise direction, the abutments are removable
10 from their supports and have alternative position of connection therewith, one position permitting angular displacement of the coupling members for one direction of rotation, and the other position permitting
15 angular displacement for the opposite direction of displacement.

In the accompanying drawing illustrating the preferred embodiment of the coupling hereinbefore referred to, Figure 1 is a side elevation; Fig. 2 is a front elevation; Fig. 3 is a section on line 3—3 of Fig. 2; Figs. 4 and 5 are sections on lines 4—4 and 5—5 respectively, of Fig. 3; Fig. 6 is a front elevation of one coupling member with its latches in radial or disengaged positions; and Fig. 7 is an elevation, on a reduced scale, of the operator's tool.

The axially alined shafts 1 and 2 may be the driving and driven shafts of the coupling, connected respectively to a driving unit such as an internal combustion engine, and to a driven unit such as an impulse starting mechanism which in turn has its driven member connected to a magneto associated with the engine for ignition purposes. In such an arrangement 3 is the driving member of the coupling and 4 is the driven member.

The coupling member 3 comprises a metal block 5 having a central opening for the reception of the end of the shaft 1, and also having side flanges 6 forming a slot for the reception of the central part of the diametrical arm 7. The block 5 is held rigidly in set position on the shaft 1 by a wedge pin 8 drawn up tightly by the nut 9 and locked by the split washer 10. The diametrical arm 7 comprises a magazine of leaf springs clamped tightly between the bearing plates 11 by bolt 12.

The coupling member 4 has a disk 13 with a hub 14 extending beyond both faces, and is fastened to a part 15 by bolts 16. The part 15 has a median web 17 with a central opening at 18 and an arcuate slot at 19. The web has an annular flange 20 on its inner face and a flange 21 on its outer face forming an annular V-shaped groove 22 with the outer rim 23. The bolts 16 have arcuate heads 24 V-shaped in end view. The bolts are inserted one at a time through the slot 19, and when their shanks 25 extend through the holes of disk 13, the part 15 may be adjudged in angular position relatively to the disk. The nuts 26 are then

screwed up tightly and locked by the split washers 27, the heads of the bolts being securely seated in the groove 22. The rim 23 is cut out at diametrical opposite places at 28 for the reception of the latches 29 which are journaled loosely on pivot pins 30. These latches have jaws 31 adapted, when turned to normal positions, to closely embrace the outer ends of the arm 7, and have fiber inserts 32 to take the wear resulting from friction. The flat spring 33 is screwed to the flange 20 and has arms extending underneath the latches, the arrangement being such that the springs tend to hold the individual latches in disengaged position 80 radially of the axis of rotation, and also in engaged position substantially parallel to the axis of rotation.

Each of the latches has two screw threaded holes 34 and 34' adapted for engagement with the stud 35. With the studs in the holes 34, and the latches in disengaged positions, the coupling member 4 is prevented from rotation in one direction, but is permitted to be turned in the other direction 90 through a limited angle less than 180°. Similarly, with the studs in holes 34', that coupling member may be turned in a direction opposite to that permitted in the former case, but likewise through an angle less than 180°.

The coupling members are accurately set on the driving and driven shafts as follows: Hub 14 of the disk 4 has a key way 36 adapted to take the key 37 on the tapered end of the shaft 2, and the end of the shaft is threaded to receive a nut 38 and split washer 39 for rigidly securing the member against angular and axial movement thereon. The part 15 is then fastened to the disk 100 by the bolts 16 in angular position predetermined as desired.

In case the driven unit is a magneto and the driven member of the coupling is the member 4, the magneto is brought to its position for maximum generation, that is to the position at which the mechanical interrupter starts to open. With the shaft 2 held in this position, the shaft 1 which may be a driving shaft connected to an internal combustion engine is turned to substantially its firing position with the piston of the proper cylinder at or near the very top of its stroke. The coupling member 3 is then turned on the shaft to its position of connection with the coupling member 4, and the latches 29 are then turned down to embrace the outer ends of the arm 7. A flat surface is then filed on the shaft 1 and the wedge pin 8 is inserted in place and drawn up tightly by the nut 9 to rigidly hold the coupling member 3 on the shaft 1 against angular and axial movement thereon.

The flat springs forming the arm 7 permit a slight amount of axial disalignement of 130

the shafts 1 and 2, and while filling the space between the jaws 31 of the latches, they permit the latches to be more easily engaged and disengaged, particularly on account of the convexity of the bearing surface of the central bearing plates 11.

In case the coupling member 4 is on the shaft of an impulse starting mechanism, and the magneto is to be turned against the normal direction of rotation to reach its angular position for maximum generation in the next impelling movement, the studs 35 are mounted in the holes indicated in Fig. 6 for rotation of the driving shaft 1 in clockwise direction as viewed from the right in Figs. 1, 3 and 5; but if the shaft 1 rotates in anti-clockwise direction, the studs are screwed into the other holes 34' of the two latches 29.

To assist the operator in releasing the latches from engaging positions with arm 7, the tool 40 has its end 41, shaped for that purpose. Its other end has two prongs 42 adapted to fit in two of the four holes 43 of the coupling member 4 to give the operator an increased leverage in turning that member against resistance, as for instance, against the stress of the impelling spring of an impulse starting mechanism.

Having thus described our invention, what we claim is as follows:

1. Means for releasably securing two coaxial shafts in a predetermined angular relation, comprising a member fastened on one shaft in angularly-adjusted position, a member fastened on the other shaft, an arm fixed to one member, and a pivoted latch carried by the other member and co-operative with the arm in but a single position so as to lock the members from displacement with the shafts in the predetermined angular relation.

2. In a releasable shaft coupling, coaxial driving and driven members, a resilient arm carried by one member, and a latch pivotally connected to the other member and movable from one position embracing the outer end of the arm to another position out of engagement therewith.

3. In a releasable shaft coupling, coaxial driving and driven members, a resilient arm carried by one member, a latch pivotally connected to the other member and movable from a radial position out of engagement with the arm to an axial position engaging the arm, and a spring tending to hold the latch in either of these two positions.

4. In a releasable shaft coupling, coaxial driving and driven members, a resilient arm carried by one member, and a latch pivotally connected to the other member and movable out of embracing engagement with the outer end of the arm.

5. In a releasable shaft coupling, coaxial driving and driven members, a diametrically

disposed resilient arm carried by one member, and diametrically disposed latches carried by the other member and movable from disengaged positions to engaged positions embracing the outer ends of the arm. 70

6. In a releasable shaft coupling, coaxial driving and driven members, a diametrically disposed resilient arm carried by one member, diametrically disposed latches carried by the other member and movable from disengaged positions to engaged positions embracing the outer ends of the arm, and a spring tending to hold the latches in either of these two positions. 75

7. In a releasable shaft coupling, coaxial driving and driven members, a radially-disposed magazine of flat springs carried by one member, and a latch carried by the other member and movable from disengaged position to engaged position embracing the outer 80 end of the magazine.

8. In a releasable shaft coupling, coaxial driving and driven members, a diametrically disposed magazine of flat springs carried by one member, and diametrically disposed latches carried by the other member and movable from their disengaged positions to engaged positions embracing the outer ends of the springs. 90

9. Means for releasably securing two coaxial shafts in a predetermined angular relation, comprising a member fastened on one shaft in angularly-adjusted position, a member fastened on the other shaft, and disengageable connecting means carried by the respective members and engageable in but one angular relation thereof to lock the members from displacement with the shafts in the predetermined angular relation. 95

10. In a releasable shaft coupling, coaxial driving and driven members, disengageable connecting means for the members, and means limiting the relative angular displacements of the members when they are disengaged by the connecting means. 105

11. Means for releasably securing two coaxial members in a predetermined angular relation, comprising an arm fast intermediate of its ends to one member and having terminal engaging portions, a pivoted latch carried by the other member in position to engage the terminal portions of the arm, and means restricting the relative movement of the members, when released, to less than the angular displacement of said terminal engaging portions, whereby the latch can be engaged with the predetermined one of the terminal portions but not with the other. 115

12. In a releasable shaft coupling, coaxial driving and driven members, a pivoted device carried by one member for engagement with the other member to hold the two members in substantially fixed relative angular position, and an abutment carried by the 125

130

pivoted member in position to limit the relative angular displacement of the members when they are disengaged.

13. In a releasable shaft coupling, coaxial driving and driven members, a diametrically disposed arm carried by one member, diametrically disposed latches carried by the other member and movable from disengaged positions to engaged positions embracing the outer ends of the arm, and abutments carried by the latches to prevent relative angular displacement of the members in one direction and to limit the relative angular displacement of the members in the other direction.
14. In a releasable shaft coupling, coaxial driving and driven members, an arm carried by one member, pivoted devices carried by the other member and movable from disengaged positions to positions engaging the outer ends of the arm, and an abutment carried by each pivoted device in position to prevent relative angular displacement of the members in one direction and to limit the relative angular displacement of the members in the other direction.
15. In a releasable shaft coupling, coaxial driving and driven members, a diametrically disposed arm carried by one member, diametrically-disposed pivoted latches carried by the other member and movable from disengaged positions to engaged positions embracing the outer ends of the arms, each of said latches having two circumferential displaced screw threaded holes, and two studs adapted to be mounted in two of the holes of the two latches for permitting limited angular displacement of the members in one direction, and adapted to be mounted in the two other holes of the two latches for permitting angular displacement of the two members in the opposite direction.

bers in the other direction each of said pivoted devices providing two mountings for the abutment to provide for the limited angular displacement in the direction desired.

16. In a releasable shaft coupling, coaxial driving and driven members, a diametrically disposed arm carried by one member, diametrically-disposed pivoted latches carried by the other member and movable from disengaged positions to engaged positions embracing the outer ends of the arms, each of said latches having two circumferential displaced screw threaded holes, and two studs adapted to be mounted in two of the holes of the two latches for permitting limited angular displacement of the members in one direction, and adapted to be mounted in the two other holes of the two latches for permitting angular displacement of the two members in the opposite direction.

In testimony whereof we affix our signatures.

WOLFGANG E. SCHWARZMANN.
FREDERICK DRAKE NORMAN.
